UNITED STATES PATENT OFFICE.

EDWARD S. MITCHELL, OF SYRACUSE, NEW YORK.

CLOTHES-PIN.

1,211,211.

Specification of Letters Patent.

Patented Jan. 2, 1917.

Application filed March 16, 1916. Serial No. 84,638.

To all whom it may concern:

Be it known that I, EDWARD S. MITCHELL, a citizen of the United States, residing at Syracuse, in the county of Onondaga, State 5 of New York, have invented certain new and useful Improvements in Clothes-Pins; and I do hereby declare the following to be a full, clear, and exact description of the invention, such as will enable others skilled 10 in the art to which it appertains to make and use the same.

This invention relates to improvements in clothes pins.

One object of the invention is to provide 15 a simple and cheap device of this character which by reason of the fact that it is formed from a single length of wire can be manufactured and sold at a low cost.

Another object is to provide a clothes pin 20 in which the jaws are so formed that a more efficient gripping action can be had in connection with the clothes and line than with similar devices heretofore.

Another object is to provide a clothes pin 25 of such construction that it may be more easily manipulated when applying the same to or removing it from the line than with similar devices heretofore.

Another object is to provide a clothes pin 30 which is particularly adapted for use in connection with the pulley lines, so that the lower lap of the line will be guided and supported by the handle portion of the clothes pin. Thus the said handle portion 35 serves a double function.

Other objects and advantages will be apparent from the following description when taken in connection with the accompanying drawings.

40 In the drawings:—Figure 1 is a front elevation of my improved clothes pin shown in connection with a double or pulley line; Fig. 2 is a vertical section on the line 2—2 of Fig. 1; and Fig. 3 is a horizontal section 45 on the line 3—3 of Fig. 1, the clothes pin being removed from the line.

Referring particularly to the accompanying drawings it will be seen that the clothes pin is made of a suitable length of wire. 50 This wire is so bent as to provide a pair of approximately parallel members 10 which

converge toward each other at one end, as shown at 11, and these ends are twisted as at 12, and this twisted portion bent upwardly and rearwardly in the form of a 55 ring, as clearly shown. The other end of each of the members 10 is connected, by means of a curved portion 13 to a downwardly extending member 14. The two members 14 are arranged in approximately 60 parallel relation in advance of the members 10, and are of a length approximately one-half of the members 10. These members 14 are connected by a transversely extending and outwardly directed curved portion 15. 65 It will be noted that the members 14 are spaced a slightly greater distance apart than the members 10 so that when the clothes line 16, and the garment 17 draped there-over are engaged between the members 10 70 and 14 there will be a tendency to kink the line at two points, that is where each of the members 10 co-operates with the member 14 to grip the line.

The portions of the members 10 below the 75 curved connecting portion 15 forms a shank which greatly helps the operator when reaching up in the air to place the device in engagement with the line. The twisted ring forms an efficient handle by means of 80 which the device can be held to apply the device to the line.

Attention is called to the fact that the present device is particularly adapted for use in connection with a double or pulley 85 line. In this instance the lower lap of the line is passed through the twisted ring so that the laps will be held in properly spaced positions, and be prevented from twisting.

What is claimed is:

A clothes pin for use in connection with an endless pulley line formed of a single piece of wire and consisting of a pair of parallel bars, a second pair of shorter bars disposed outwardly of and at a greater distance apart than the first bars, said shorter bars extending into a plane approximately coincident with the plane of the longer bars, whereby a twisting clamping action is produced between the longer and shorter bars, 95 curved members connecting the longer and shorter bars at one end, a curved member 100

connecting the other ends of the shorter bars, the remaining ends of the longer bars being twisted and formed into a rearwardly and upwardly extending open ring to provide a hand grip, said ring also serving to receive and guide the lower lap of an endless pulley line.

In testimony whereof, I affix my signature, in the presence of two witnesses.

EDWARD S. MITCHELL.
